TRAFFIC GUARD

Eugene V. Camp, Atlanta, Ga.

Application November 9, 1935, Serial No. 48,962

17 Claims. (Cl. 256—13.1)

This invention relates broadly to safety devices, and more specifically, to a new and improved spring post for use in conjunction with highway guard rails.

Modern high speed motor cars and a national system of good roads have given rise to divers problems in the preserving and protecting of human life and the keeping of property damage from accidents, at a minimum. In this connection the present day resilient plate type guard rail as disclosed in my basic Patent No. 1,793,673 has become an increasingly important factor in guarding and making safe public highways, the introduction of the device embodying the fundamental concept of said patented invention having revolutionized the guard rail industry in the United States and abroad. Guard rail assemblies embodying the essence of that invention, which may be said to comprise a sheet metal band maintained entirely to one side of a series of supports under longitudinal tension, have been generally successful and are conceded to represent the best known method to date of dealing with existing traffic problems.

The weakest part of such structures is the posts which support the guard rail proper, such posts usually consisting of conventional wooden members which are prone to rot out, decay, become brittle so as to snap off under comparatively light impacts; push out of the ground, or otherwise fail to efficiently perform the function for which they are intended. A guard rail assembly is no stronger than the posts thereof, and since the rail proper is usually designed to resist tremendous forces, such members often having a tensile strength of over one hundred thousand pounds, it is towards the weak link in the assembly—the posts—that this invention is primarily directed.

An object of the instant invention is to provide a guard rail having spring metal posts which, upon impact, yield a predetermined degree before becoming rigid.

Another object is to provide a durable guard rail post that will not rot or decay, but which to all intents and purposes will be as permanent as the metal rail with which it is associated.

Another object is to provide means for anchoring and securing in the ground a guard rail of the foregoing character.

Another object is to provide means for offsetting such a post in a guard rail assembly in such a manner as to reduce or eliminate the danger of an impacting vehicle coming into contact with said post.

Another object is to provide unique means for

checking the movement of a resilient multiple leaf spring guard rail post after it has traveled a predetermined distance upon impact.

Another object is to provide strength and permanence in a guard rail post.

A still further object is to provide means for passing the plate element of a guard rail, through its supporting post, in such a manner as to achieve certain structural advantages made clear hereinafter.

Another object is to provide means for imparting tension to a resilient metal plate passed through its supporting post.

Another object is to provide cheapness of construction and economy in manufacture in highway guard rails embodying the instant invention.

These and other objects made apparent during the further progress of this specification are accomplished by means of my new and improved resilient spring guard rail post, a full and complete understanding of which is facilitated by reference to the drawing herein, in which:

Fig. 1 is an enlarged side view of a post embodying the instant invention, associated with an impact member shown in section, said view being taken with the line of vision parallel to the roadway.

Fig. 2 is a front elevational view of the structure illustrated in Fig. 1, as seen from the highway, said view being fragmentary in part.

Fig. 3 is a top plan view of the structure disclosed in Figs. 1 and 2.

Fig. 4 is a horizontal cross-sectional view of the device, taken substantially along the line IV—IV of Fig. 1, looking in the direction of the arrows.

Fig. 5 is a horizontal cross-sectional view of the post taken substantially along the line V—V of Fig. 1.

Fig. 6 is a fragmentary side view of another form of the instant invention, in which the plate member of the rail is passed through its supporting post.

Fig. 7 is a front view of the structure illustrated in Fig. 6.

Fig. 8 is an enlarged horizontal cross-sectional view of the structure illustrated in Figs. 6 and 7, said view being taken along the line VIII—VIII of Fig. 7 and turned through an arc of ninety degrees.

Fig. 9 is an enlarged fragmentary front view of a post of the instant type, illustrating a modification in the means by which the transverse movement of the spring post is checked after said post has yielded a given distance upon impact.

Fig. 10 is a top view of the structure illustrated in Fig. 9.

Like numerals indicate corresponding parts throughout the various figures of the drawing.

While several different structural forms of the road guard have been illustrated in the accompanying drawing, it will be understood that each of them involves the same general operative principles and includes mechanical equivalent elements to effect the same specific results. It will also be understood that the disclosures of Figs. 1 to 10 inclusive are of individual units in a complete guard rail assembly, it being contemplated that all units illustrated in the drawing herein shall be multiplied as desired in erecting a highway guard for a given location.

Referring now to the drawing, Figs. 1, 2, and 3, my invention contemplates a post of spring metal having a front element 10 and a rear element 11, which elements are preferably formed respectively convex and concave, this providing additional strength to the post elements without, however, depriving them of their inherent resilience. 10 and 11 are disposed in a generally parallel relationship to each other with their broad dimensions facing the highway (Fig. 3), and are illustrated joined together at a point somewhat below that to which the posts will normally be positioned in the ground, by means of bolts 12 and 13 passed through suitable apertures providing for that purpose in a reinforcing and/or spacing web 14 (Fig. 4), which member may be stamped or otherwise fabricated from suitable metal.

To assist in stabilizing the posts in the ground, fins or webs 15 and 16 are provided, these elements being formed of light metal, and are substantially V-shaped, with both ends of the V attached to the post as by passing bolts 12 and 13 through holes provided in said ends for such purpose, this ultimate triangular structure affording additional rigidity and strength to a member formed of light material. Spacer 14 is so formed that there may be some articulation between this element and 10 or 11 when the resilient feature of the post is brought into operation.

To further stabilize the post in the ground an angle plate 11a may be disposed between 10 and 11 at their lower ends, thereby forming, in effect, a foot at this point; and a third fin 17, similar in shape and fabrication to fins 15 and 16 may likewise be associated with said ends, a pair of bolts 18 and 19 serving to fasten 17 to the bottom of 11 and to join together the two post elements and stabilizing foot in a rigid manner. The vertex of V-shaped fin 17 may be secured to foot 11a as by a weld 20; the assembled structure providing a device which when placed in the ground resists deflection transversely and/or laterally, yet which is light in weight and economical to manufacture. The posts may be placed in the ground in any suitable manner, and may be secured in position with earth, rock, or other suitable material.

Attention is now directed to the upper portion of element 10, which member may be straight, or formed with an off-set as shown in Fig. 1, this construction being deemed preferable because it reduces or eliminates the danger of a projecting portion of an impacting vehicle coming into contact with the post, with attendant damage both to said structure and to the vehicle, such an impact tending to stop the car suddenly by turning it into the rail, which is in direct

contrast to the approved manner of operation of the modern resilient type guard rail which is intended to glide the impacting vehicle along the smooth surface of the rail and ultimately to bring such back into the highway, such action ordinarily being accompanied by deceleration, and the forces set up by the impact being distributed throughout the entire guard rail structure and dissipated without severe injury to, or failure of the rail in the ordinary case. A commercially desirable manner of forming the off-set is indicated in Fig. 1, in which front element 10 is bent forward at a point approximating that at which the post will be placed in the ground, said point being designated 10a in the drawing; and rear element 11 at 11b likewise bent at an even sharper angle, to provide desired spacing between the post elements, and further, to bring said elements together in sliding engagement at their upper portions, as will be explained more in detail during the further progress of this specification.

The top of 10 may be bent as at 10b to form a substantially right angle with the ground when the post is placed therein, and to provide a suitable surface to which is anchored an impact member 21, while the extreme upper portion of 10 may be turned rearwardly to form a cap 10c, which acts as a supplemental stop means to the upward movement of 11 when the face of the post is impacted.

Rear member 11 is bent as at 11c to lie in a plane parallel to that established at 10b, and a sliding contact is provided near the tops of 10 and 11 by a limited slot hole 11d through which is passed a bolt 22, said bolt being first passed through a suitable aperture in 10, this construction making it possible for the two elements of the post to yield a predetermined degree upon impact before assuming a rigid, truss-like form calculated to resist heavy stresses, the position of the elements under said latter conditions (as impacted) being indicated by the dotted lines in Fig. 1. Cap 10c further serves to check the upward movement of 11 in relation to 10, it being apparent that when 11 has moved to the limits fixed by slot 11d, the top of said rear member is in engagement with the underside of the cap.

An alternate method of accomplishing the above-described sliding action is suggested in Figs. 9 and 10, in which the upper portions of 10 and 11 are provided with a series of notches 23 and 24 along their sides, which notches are dove-tailed together in such a manner as to allow rear member 11 to slide upwardly a given distance before being checked by the contact of notch 24 against notch 23, the space 25 between the notches allowing for this movement. If desired, element 10 may be provided with a cap such as 10c (Fig. 1) to act as a further stop element in conjunction with said series of notches. It is to be noted that the upper portions of 10 and 11 (Figs. 9 and 10) are slightly sprung together so that the two elements may slide one on the other, but with material frictional spring resistance tending to prevent such sliding. This arrangement aids substantially in supporting a load against the face of the rail before the rear element reaches the stop, the snubbing action present helping to absorb the shock without bringing the full spring effect of the post into action, thereby making possible the resistance of a given force with a lighter spring action than would otherwise be possible.

It will be apparent to those skilled in the art that if desired, the sliding stop-joint arrangement described herein may be provided at the bottom ends of the post instead of the top, or at both top and bottom when given circumstances warrant.

Impact member 21 may comprise a resilient strip of sheet metal or an element or elements having a beam-like action, any suitable collision-resisting structure coming within the scope of the instant invention.

Special attention is now directed to the embodiment of the instant invention disclosed in Figs. 6, 7, and 8, in which the two elements of the post instead of having their concave and convex surfaces opposed to each other as in the form described up to this point, are so positioned that said surfaces are approximately parallel to each other, element 11 being shown in the drawing as a special rear member having somewhat more of a curve in its face than does front element 10, and having its sides turned towards the rear, both for the purpose of affording additional strength to the device and to eliminate sharp edges facing the roadway. A sliding plate 26 is provided to the rear of 11, and a bolt 27 is passed through 10, through a suitable slot 11e in 11, and through said plate. At the top, a second bolt 28 is passed through 10 and engages plate 26 at the rear, a notch 11f in 11 furnishing additional stop means in conjunction with bolt 28 when 11 is moved upwardly upon impact. A cap such as 10c may provide further stop means.

It is to be especially noted that rail or impact member 21 is passed between post elements 10 and 11, which arrangement, in view of the concave structure of 10 and 11, provides a means of putting rail 21 under longitudinal tension, it being apparent that upon a tightening of bolts 27 and 28, the rail is deflected to one side and in such a contour that there is a tendency to shorten said rail, thereby putting the member under tension.

It is likewise apparent that member 10 is pulled back of the general alignment of the rail by the foregoing action (Fig. 8), thereby eliminating any obstruction to contacting vehicles.

From the foregoing it is patent that I have disclosed a new and useful resilient spring post for use in guard rail assemblies. That said post upon impact gives a predetermined degree, thereby cushioning the shock and providing a spring action heretofore lacking in guard rail posts. That upon reaching the limit of its resilience, the post assumes a rigid form capable of resisting large stresses, and in such form serves as a safe and efficient supporting member. That this resilient-truss effect is highly desirable in dealing with present-day highway problems. That the post is securely and ingeniously fixed in the ground by special means provided for that purpose. That the device is economical to manufacture, and capable of resisting severe impacts, although the amount of metal required for each unit is comparatively small. That the post is comparatively permanent, in keeping with the remainder of modern guard rail structures; easy to maintain; not subject to change with the passage of time and influence of weather, as in the case of wooden posts; and is pleasing in appearance.

It is further apparent that I have disclosed a new and useful means of associating a guard rail plate with a post, the essence of which method

consists of passing the rail through the post, with advantages set forth above.

While I have described the post herein with considerable detail, I do not intend to thereby limit myself, but on the contrary intend that the appended claims shall be accorded a liberal interpretation and a broad range of equivalents in keeping with the essence of my invention.

I claim:

- 10 1. A traffic guard comprising a series of posts, said posts consisting of a plurality of springs in generally parallel relationship to each other, means slidably joining said springs at one end, a spacing member intermediate the ends of said springs, a plurality of stabilizing fins attached to the lower portions of said springs, an anchoring foot at the bottom of said springs, means uniting said springs at their bottom ends, and a flexible impact member disposed longitudinally of said posts.
- 15 2. A traffic guard comprising a series of posts, said posts consisting of a pair of springs in generally parallel relationship to each other, means slidably joining said springs at one end, a spacing member intermediate the ends of said springs, V-shaped stabilizing fins adjacent said spacing member, means uniting said springs at their other end, a V-shaped stabilizing fin adjacent the bottom ends of said springs, and an impact member associated with said posts and disposed longitudinally thereof.
- 20 3. A traffic guard comprising a series of posts, said posts consisting of a plurality of springs, and an impact member disposed longitudinally of said posts.
- 25 4. A traffic guard comprising a series of leaf spring posts, and an impact member disposed longitudinally and entirely to one side of said posts.
- 30 5. A guard rail comprising a flexible sheet metal band disposed entirely to one side of a series of spaced resilient spring metal posts.
- 35 6. A guard rail comprising a flexible sheet metal band disposed entirely to one side of a series of leaf spring metal posts.
- 40 7. A traffic guard comprising a series of posts, said posts consisting of a pair of resilient springs having concave surfaces disposed in generally parallel relationship to each other, a sliding plate to the rear of said springs, means slidably joining said springs near their tops, stop means associated with said springs for limiting the upward travel of the rear spring, means for drawing said springs together at their upper portions, and a resilient sheet metal band disposed between said springs and in engagement with the concave surfaces thereof in such a manner that when said tightening means is operative, said metal band is drawn into the indentation provided by said concave surfaces, thereby putting said band under longitudinal tension.
- 45 8. A traffic guard comprising a series of spring metal posts, and a resilient impact member disposed to one side of said posts with a portion of said impact member at the posts passed between portions of said posts.
- 50 9. A traffic guard comprising a series of posts, said posts consisting of a front spring and a rear spring in generally parallel relationship to each other, means including a slotted joint for slidably joining said springs near one end, a cap integral with said front spring for limiting the movement of the rear spring, means for stabilizing said posts when such are placed in the ground, an impact member disposed longitudinally of said
- 55
- 60
- 65
- 70
- 75

posts, and means for off-setting said posts in relation to the road in such a manner that said impact member is nearest the line of traffic and the remainder of said post recedes transversely from the line of travel.

10. A traffic guard comprising a series of offset resilient spring metal posts and an impact member disposed longitudinally thereof.

11. A traffic guard comprising a series of spaced posts, said posts consisting of a pair of springs in generally parallel relationship to each other, opposed curved surfaces at one end of said springs, a series of spaced notches along the sides of said end portion whereby said springs are dove-tailed together and a limited vertical movement between said elements provided; and an impact member disposed longitudinally of said series of posts.

12. A traffic guard comprising a series of spaced supports, said supports consisting of a front and a rear element in generally parallel relationship to each other, means joining said elements in frictional engagement whereby they give a predetermined degree upon impact, said frictional engagement affording a snubbing action tending to retard such movement, and an impact member disposed longitudinally of said series of supports.

13. A traffic guard comprising a series of spaced posts, said posts consisting of a plurality of springs in generally parallel relationship to each other, opposed curved surfaces at one end of said springs, a series of spaced notches along the sides of said end portion whereby said leaf ends are dove-tailed together in frictional engagement and a limited vertical movement be-

tween the springs afforded, said movement being retarded by the snubbing action produced by said frictional engagement; and an impact member disposed longitudinally of said series of posts.

14. A traffic guard comprising a series of spaced resilient spring metal posts, V-shaped fins attached to the broad surfaces of said posts at points below which said posts will normally be positioned in the ground, and an impact member extending from post to post.

15. A traffic guard comprising a series of spaced supports, a V-shaped stabilizing fin attached to said supports at a point below which said supports will normally be placed in the ground, and an impact member extending longitudinally of said series of supports.

16. A traffic guard comprising a series of posts, said posts consisting of a plurality of springs in generally parallel relationship to each other and with their broad surfaces parallel to the highway, means slidably joining said springs at one end, a spacing and reinforcing member intermediate the ends of said springs and below the point to which said posts are contemplated to be normally placed in the ground, a plurality of stabilizing fins fastened to the lower portions of said springs, said fins comprising substantially V-shaped members formed of light metal and attached to the flat surfaces of said springs so as to form a triangular structure; and an impact member disposed longitudinally of said posts.

17. A guard rail comprising a series of spaced resilient spring metal posts, and a sheet metal band passed through said series of posts longitudinally thereof.

EUGENE V. CAMP.
